UNITED STATES PATENT OFFICE.

CHARLES W. T. DAVIES, OF NEW YORK, N. Y.

BUTTONHOLE FOR WEARING-APPAREL.

1,147,485.

Specification of Letters Patent. Patented July 20, 1915.

Application filed May 5, 1911, Serial No. 625,381. Renewed May 7, 1915. Serial No. 26,658.

To all whom it may concern:

Be it known that I, CHARLES W. T. DAVIES, a subject of the King of Great Britain, residing at New York, county of New York, and State of New York, have invented certain new and useful Improvements in Buttonholes for Wearing-Apparel, of which the following is a specification.

This invention relates to closed buttonholes for articles of wearing apparel.

The present invention has for its object the provision of a closed buttonhole guarded by a locking member of novel arrangement and construction for use on any article of wearing apparel where it is desired to button together different parts, its purpose being to confine the bar, link, shank, or shaft of a stud or button, after penetration of its enlarged head, to a restricted space and, to provide, when the material of the article is of a stiff nature, a larger buttonhole than usual for the easy entry of an enlarged head, with subsequent retention of said locking member in place when in operative position.

The invention may be applied to various articles of wearing apparel and variously formed, but is particularly adapted for use on cuffs, although I do not wish to be understood as restricting its use to any particular article of apparel.

The invention may be carried out in various ways, in all cases through the agency of a movable tab which, however secured to the article, integrally or otherwise, is separate and free from the closed buttonhole, but so fixedly and flexibly positioned in relation to the same that it is adapted in a variety of ways to lock the stud within a prescribed portion of the closed buttonhole, and be retained in such locking position by means of coöperation with a receptacle or retaining device on the article of wearing apparel itself.

In carrying out the invention, the button-hole is of the closed type, and the locking tab associated therewith is disposed in overlying relation to the article and extends from one edge of the buttonhole to and beyond an opposite edge thereof and defines a constricted but open portion of said button-hole, confines the stud therein and further retains its closed position by coöperation with a receptacle or retaining device on the article of wearing apparel itself.

One embodiment of the invention is shown in the accompanying drawing which illus-

trates the invention applied to a portion of an article of wearing apparel.

A portion of the article of wearing apparel is shown at 1^c and has a buttonhole 33. At one margin intermediate the ends of the buttonhole 33, a single flap or tab 34 is attached to the article of apparel 1^c. The tab or flap may fold across the buttonhole or be tucked into it, as shown by dotted lines, to provide at one or both ends of the buttonhole a constricted part thereof for engagement with the link of the stud or button. Close below the main buttonhole is shown a smaller buttonhole 33^a for receiving the tip of the tab and disposing of its end, this accommodation serving to enhance the locking action of the two coöperating parts. Any other modification, such as a pocket, loop, or even stitching would serve the purpose of the buttonhole 33^a so long as the locking member is free for manipulation on either side of the jaws of the buttonhole.

The flap or tab 34 guards the buttonhole and constricts it so that the shank of the link, stud, fastener or button is confined to a constricted portion of the buttonhole. The length of the buttonhole, however, permits the head of the stud, button, or fastener to be readily passed therethrough before the flap or tab 34 is positioned in overlying relation to the buttonhole, but after the stud, fastener, or button has been passed through the buttonhole, the tab or flap 34 is then arranged, as set forth, to hold the shank of the stud or fastener in a constricted portion of the buttonhole.

The tab or flap may be made as wide as, wider, or narrower than the buttonhole it overlaps, achieving its locking purpose, when broader, between the article of apparel and the enlarged head of the stud or fastener; when narrower, by being held between the opposing edges of the buttonhole, or, in either case, by a further retaining member on the article of apparel itself such as I have shown at 33^a, or its equivalent. The locking member is always secured at a point adapting it to overlap the buttonhole in which the stud, button, or fastener is held, except at that point where the shank thereof protrudes.

Having thus described my invention, what I claim as new and desire to secure by Letters Patent, is:

An article of apparel provided with a buttonhole having a complete continuous

margin, in combination with a movable flap carried by said article, said flap being disposed in overlying relation to said article of apparel and extending from one edge to and 5 beyond an opposite edge of said buttonhole so as to define a constricted portion of the buttonhole open for the retention of a shank therein, and means on the article itself, in-

dependent of the buttonhole, adapted to receive and hold the free end of the flap. 10

In testimony whereof, I hereunto affix my signature in presence of two witnesses.

CHARLES W. T. DAVIES.
